UNITED STATES PATENT OFFICE.

HENRY ALBERT PERSHING, OF SOUTH BEND, INDIANA.

COMBINED PETIT LEDGER AND BLOTTER.

SPECIFICATION forming part of Letters Patent No. 367,924, dated August 9, 1887.

Application filed April 1, 1887. Serial No. 233,271. (No model.)

To all whom it may concern:

Be it known that I, HENRY ALBERT PERSHING, a citizen of the United States, residing at South Bend, in the county of St. Joseph and 5 State of Indiana, have invented certain new and useful Improvements in Combined Petit Ledger and Blotter; and I do declare the following to be a full, clear, and exact description of the invention, such as will enable others skilled in 10 the art to which it appertains to make and use the same, reference being had to the accompanying drawings, and to the letters and figures of reference marked thereon, which form a part of this specification.

15 Like letters refer to the same parts throughout the several views.

This invention relates to certain new and useful improvements in devices for the purpose of keeping the transient or trivial accounts of 20 merchants in alphabetical order in a systematic, compact, and convenient form for reference.

The invention is particularly designed as an improvement upon the device shown and described in the Patent No. 323,729, dated August 4, 1885.

In the accompanying drawings, which form a part of this specification, Figure 1 is a perspective view of my improved ledger closed. 30 Fig. 2 is a similar view with the top cover thrown back. Fig. 3 is a similar view with the top thrown back and the tablets partially turned on their pivot.

Referring to the details of the drawings, A 35 and B are two stiff covers, connected by a flexible back, a. In the upper corner of the leaf B, I place the pivot or staple C.

D is a tablet fixedly secured to said cover B in any suitable way, preferably by the staple 40 d, and a like staple in one or more of its corners, so that the said tablet may be removed when it has been filled up or when desired. The tablet consists of a quantity of blank

leaves, bill-heads, or the like, separated by blank leaves, each having a different letter of 45 the alphabet, into nine separate parcels, each separating blank leaf projecting below the bill-heads sufficiently to expose the letters of the alphabet thereon, thus forming a marginal index.

50 F and G are similar tablets pivotally secured at one corner only by the staple C, so that said tablets can be revolved on said staple when desired, as indicated in Fig. 3.

By this construction I provide a petit ledger in which the account of any one individual may be readily turned to, and if the account of the individual in question should happen to be upon the second or third tablet, it can be reached by simply turning the first or the first 60 and second tablets, as the case may be, upon the pivot C, thus avoiding the necessity of opening the book further, and if occasion should require the three tablets may be all displayed at the same time, which the construction of 65 the Patent No. 323,729 prevents.

It is evident that, although I show and prefer to use three tablets, the number may be varied without departing from the spirit of my invention.

70 What I claim to be new, and desire to secure by Letters Patent, is—

The combination, with the covers A B, flexible back a, connecting the same, and the tablet D, fixedly secured to the inner face of one 75 of said covers, of the staple C and a plurality of tablets, indexed as described, and pivotally secured at one corner by said staple, substantially as described, and for the purpose specified.

80 In testimony whereof I affix my signature in presence of two witnesses.

HENRY ALBERT PERSHING.
